UNITED STATES PATENT OFFICE

ROBERT W. KALTENBACH, OF CLEVELAND HEIGHTS, OHIO

PLATEN LOCK FOR CAR DUMPERS

Application filed March 10, 1930. Serial No. 434,558.

This invention relates to car dumpers, which are used for dumping the contents of a railroad car by inverting the car while it is held within a cradle. One form of dumper 5 heretofore used utilizes a platen, which carries the car supporting tracks, and which is adapted to be shifted with relation to the cradle until one side of the car engages the buffers against which it is held during the dumping operation. Counterweighted cables are adapted to engage the top of the car, and to hold it on the tracks while it is in the inverted position. Frequently, a car will be so loaded however, that lumps of coal will 10 be caught between the cables and the top edge of the car, and will thereby prevent the cables from directly engaging the car. Then, as soon as the weight of the car is thrown onto the cables, the coal is crushed, with the result 15 that the car is subjected to a jerk, which in some cases has caused it to leave the rails. This leaves the platen free to move with reference to the cradle, so that when the car is jerked back, the wheels are out of registration 20 with the tracks and the car is derailed. 25

One form of mechanism heretofore used for holding the platen against movement with relation to the cradle under the conditions described has comprised a rack and a 30 pawl, which is adapted to coact therewith and to lock the platen in the desired position. Such apparatus is not only expensive however, but is not foolproof, as there is a likelihood of the pawl failing to engage the rack tooth at the desired time due to the lost motion between the pawl and rack tooth.

One of the objects of the present invention, therefore, is the provision of a simple device, which will effectively lock the platen against 40 movement with relation to the cradle, while the cradle is tilted even though the car wheels should leave the rails momentarily during the dumping operation. A further object is to make a device, which will be fool-proof in 45 operation, and which will be more economical to manufacture and assemble than any device heretofore used.

As the rack and pawl mechanism heretofore used has been operated under the action 50 of gravity and as the mechanism employed

is not sufficiently accurate for accomplishing the desired result, it is also one of the objects of my invention to provide a mechanism which is operative to produce an effective locking action between the platen and cradle 55 independently of the action of gravity.

Referring now to the drawings, Fig. 1 is a vertical transverse section through the cradle part of a car dumper cradle embodying my invention; Fig. 2 is a section taken on the line 2-2 in Fig. 1; Fig. 3 is a vertical transverse sectional view through a car dumper cradle showing a modification of my invention; Fig. 4 is a section taken on the line 4-4 in Fig. 3; Fig. 5 is a vertical section 35 showing another modification of my invention; Fig. 6 is a section taken on the line 6-6 in Fig. 5; Fig. 7 is a vertical transverse section through the cradle shown in Fig. 1 with the cradle in tilted position; Fig. 8 is a wiring diagram, and Fig. 9 is a diagrammatic view showing the relationship between the switch contact members when the cradle has reached the upper limit of vertical travel 70 with reference to the frame. 75

My invention is shown in connection with a car dumper having a cradle 10 which may carry rollers 11 on which a platen 12 is supported. The platen is shown as having tracks 13 on which a car 14 is adapted to be supported during the dumping operation. Normally, the platen in the position shown in Fig. 1 has the tracks in registration with the approach and run-off tracks (not shown) respectively. In such position, the side 15 of the car is out of contact with the buffer 16 on the cradle. During the initial movement of the tilting operation, the platen is moved laterally until the side of the car engages the buffer. The present invention is not concerned with the mechanism for effecting such lateral movement but is concerned with means for securely locking the platen against further movement after the side of the car 80 engages the buffer. 90

One form of mechanism which has been found to be satisfactory for returning the platen to the normal position at the end of the tilting operation, utilizes a bell crank lever 20 which is pivoted intermediately at 21 95

to the cradle. One end of the lever is pivotally connected at one end thereof, as by a link 22 to the platen, while the other end is provided with a roller 23 for engagement with 5 an abutment (not shown).

My invention provides an operative connection between the cradle and platen which permits relative movement at the start, and at 10 the end of the tilting operation, but which prevents relative movement while the car is inverted. To this end, I utilize a brake which is adapted to hold the platen against movement with relation to the cradle and which is adapted to be locked either manually or automatically 15 at the desired time.

In the form shown in Fig. 1, the brake is electrically operated and is operatively connected to that part of the bell crank lever which forms the arm 25. To this end, I have 20 shown a bracket 26, which is rigidly mounted on the arm 25, and which is pivotally connected at 27 to a rod 28. The opposite end of the rod is shown as being slidably mounted in a saddle 29, and as being provided with 25 rack teeth on the upper side thereof. The saddle is pivotally hung upon a shaft 31, which is shown as being journaled in suitable bearing blocks 32 and 33 upon the cradle structure. The shaft has a pinion 34 rigidly 30 mounted thereon for engagement with the rack and has a drum 35 positioned at the outer end thereof. Brake shoes 36 are then arranged to act upon the drum either by any suitable electrically or mechanically operated 35 means.

It is my desire that the brake mechanism be released to permit the necessary movement of the platen with reference to the cradle until the car has engaged the buffer, 40 and preferably until the cradle has tilted to such extent that all slack between the trucks and rails will have been taken up. Then, it is my desire that the brake be locked and maintained in such condition until the contents of the car are emptied and the cradle is on the return movement. At such time, the 45 brake can be released so as to permit return movement of the platen to the normal position.

When an electric brake is used for this purpose, provision can be made in the circuit for a contact switch that will be automatically closed as the cradle reaches a predetermined 50 position on the forward motion, and automatically opened when the cradle reaches the same position on the return motion.

A wiring diagram illustrated in Fig. 8 shows a source of supply 40 in circuit with an electro-magnetic brake mechanism illustrated 55 in general at 41 and a circuit controller. The controller is in the form of a switch having a stationary contact member 43 and a movable contact member 44. The stationary member may be mounted on the car dumper frame 9 and the movable member may be mounted on

the cradle, and the relationship may be such that the circuit is closed at any desired position of the cradle with reference to the frame. In Fig. 9 for example, the cradle is shown at the upper limit of vertical movement with 70 reference to the frame, at which time the movable contact 44 is out of engagement with the stationary contact 43. After the cradle has been tilted a predetermined degree however, such as is shown by the broken lines in 75 Fig. 8, the movable contact engages the stationary contact, and thereby completes the circuit through the electromagnetic brake mechanism. To allow for movement of the cradle with reference to the frame, one of the 80 wires 8 is shown as depending in a loop from the stationary contact member to the cradle.

In Figs. 3 and 4, I have shown a modification of my invention which obviates the necessity for the use of the rack and pinion to connect the brake drum to the bell crank lever. I accomplish this result by mounting the 85 brake drum directly upon a shaft 50 which forms the fulcrum of the bell crank lever.

In Figs. 5 and 6, I have shown still another modification for eliminating the rack and pinion connection. In the arrangement shown, the drum is supported in the same manner as that illustrated in Fig. 1 but the pinion is replaced by a sprocket sheave 55 around which 95 a chain 56 is adapted to extend. One end of the chain is connected to the bell crank lever at 57 above the fulcrum, and the other end is connected at 58 below the fulcrum.

With both modifications, the circuit arrangement is the same as that described for use in connection with the apparatus illustrated in Fig. 1, in that the drum is arranged to rotate freely until all of the sidewise slack movement of the trucks shall have been taken up. Thereafter, the brake is locked and is maintained in such condition until the cradle on the return motion shall have reached the point at which the brake was locked. At such point, it is released. 100

While I have described my invention in connection with the use of an electro dynamic brake, which is adapted to be released and locked automatically, nevertheless it is to be understood that if desired, the brake may be locked and released manually by the operation of suitable brake control levers within reach of one of the operators. 110

From the foregoing description, it is obvious that my invention provides a simple and effective automatic means for permitting necessary movement of the platen with reference to the cradle at the desired time, and yet automatically locks it against such relative movement while the car is inverted. It 125 is obvious moreover, that the locking can be effected without the occurrence of any lost motion between the platen and cradle. This, therefore, eliminates the possibility of the platen being free to move out of position after 130

being released from pressure due to the force exerted by the weight of the car, load and trucks upon the crushing of a lump of coal which may have been lodged between the car and cable.

I claim:

1. In a car dumper, the combination with a tilttable cradle, of a car supporting platen movably mounted thereon, a locking device on the cradle, means for connecting said device to the platen, and electro-magnetic means acting upon said device for locking it, whereby the platen may be locked against movement in either direction with reference to the cradle and independently of a car on the cradle.

2. In a car dumper, the combination with a cradle, of a car supporting platen movably mounted thereon, a member mounted for rotation on the cradle, means connecting the member and platen for moving the member whenever the platen is moved with relation to the cradle, and electrically actuated means for locking the member against rotation when the cradle is tilted, whereby the platen may be locked against movement in either direction with reference to the cradle.

3. In a car dumper, the combination with a tilttable cradle, of a car supporting platen shifttable laterally thereon, a member rotatably mounted on the cradle, a system of linkage connecting the member to the platen for moving the member whenever the platen is moved with relation to the cradle, a brake adapted to engage the member and electro-magnetic means for locking the brake whereby the platen may be locked against movement with reference to the cradle.

4. In a car dumper, the combination with a cradle member, of a platen member movably mounted thereon, a friction drum mounted for rotation on one of said members, means connecting the drum to the other of said members for rotating the drum whenever the platen is moved with relation to the cradle, and means engaging the drum for locking it against rotation whereby the platen may be locked against movement in either direction with reference to the cradle.

5. In a car dumper, the combination with a cradle, of a member mounted for rotation thereon, a platen movably mounted upon the cradle, means including a rack and pinion for connecting the member and platen, and a brake adapted to engage said member to lock it against rotation whereby the platen may be locked against movement with reference to the cradle.

6. In a car dumper, the combination with a cradle, of a platen movably mounted thereon, an arm pivotally mounted upon the cradle, means connecting the arm to the platen, a drum, means for moving the drum with the arm, a brake engaging the drum, and means for locking the brake, whereby the

platen may be locked against movement with reference to the cradle.

7. In a car dumper, the combination with a cradle, of a platen movably mounted thereon, a lever pivotally mounted on the cradle 70 means for connecting the lever to the platen to move it with reference to the cradle, a drum rotatably mounted upon the cradle, and mechanism including a rack and pinion for connecting the drum to the arm, whereby 75 movement of the arm effects rotation of the drum, and a brake operating upon the drum to lock it against rotation, whereby the platen may be locked against movement with relation to the cradle.

8. In a car dumper, the combination with a cradle, of a platen movably mounted thereon, an arm pivotally mounted on the cradle, 80 means for connecting the arm to the platen, a drum rotatably mounted upon the cradle, 85 mechanism including a flexible member for connecting the drum to the lever, and a brake acting upon the drum to lock it against rotation whereby the platen may be locked against movement with relation to the cradle. 90

9. In a car dumper, the combination with a cradle, of a platen movably mounted thereon, an arm and a drum mounted upon a common point on the cradle, means for connecting the arm to the platen, and mechanism 95 acting upon the drum to lock it against rotation, whereby the platen may be locked against movement with relation to the cradle.

In testimony whereof, I hereunto affix my signature.

ROBERT W. KALTENBACH.
